UNITED STATES PATENT OFFICE

SHEPARD W. WHITEHURST, OF FORT WORTH, TEXAS

CARBURETOR

Application filed May 13, 1930. Serial No. 451,890.

My invention relates to carburetors; and the object is to provide carburetors which are highly useful and efficient for general purposes; to provide carburetors which have no float valves; which have all adjustments external, which have fuel ports that feed at all speeds of the engines in proportion to the air intake. Another advantage is that the carburetor has no choke and does not waste gasoline or fuel in starting the engine. Another advantage is that the needle valve rises in proportion to the amount of air passing through the air intake and spreads the fuel over the head of the needle valve seat above the air intake for causing a thorough mixing of the fuel and air which passes through the ports of the cup valve and the spider. Other objects and advantages will be fully explained in the following description and the invention will be more particularly pointed out in the claims.

Reference is had to the accompanying drawing which forms a part of this application.

Fig. 1 illustrates the carburetor connected with a manifold.

Fig. 2 is a vertical section of the carburetor parts on an enlarged scale.

Fig. 3 is a side elevation of the cup valve which is in the sleeve valve.

Fig. 4 is an enlarged side elevation of the sleeve valve.

Fig. 5 illustrates a variation in connecting the carburetor to the manifold.

Similar characters of reference are used to indicate the same parts throughout the several views.

The carburetor is provided with a casing 1 having fuel intake 2 integral therewith and a nipple 3 forming an adjustment for the plug 4 which is provided with a seat 5 for the needle valve 6. The nipple 3 is integral with the casing 1 and is interiorly threaded to receive the plug 4 which is threaded and screwed into the nipple 3 and forms the adjuster for the needle valve seat 5. The nipple 3 has an interior cavity 7 which forms a chamber for containing a head of fuel. The adjuster 4 has a tubular passage 8 for delivering gasoline to the cup valve 9. The

amount of gasoline or fuel delivered to the cup valve 9 is controlled by the needle valve 6. The needle valve is tapering and the passage is tapering adjacent to the valve 6. The needle valve 6 has a stem 10 which projects loosely through an opening in the top of the cup valve 9 and is provided with a nut 32 rigid therewith and is raised by the cup valve 9 so that fuel will be drawn up in proportion to the height the cup valve is raised. A spring 11 is mounted on the needle valve about the stem 10 and between the valve 6 and the top of the cup valve 9. A spider 12 is formed integral with the cup valve 9 to form a guide for the needle valve 6. The spider 12 acts as a guide to direct the needle valve 6 should the valve 6 ever be carried above its seat 5. A spider 13 is screwed down into the casing 1 which is threaded to receive the spider 13. A spring 14 engages a boss 15 and bears on the valve 9 for holding the valve 9 yieldingly down except when the engine is running.

The explosive mixture escapes from the cup valve 9 through the ports 16 into the chamber 17 and the amount of explosive mixture that passes through these ports is in proportion to the height the cup valve 9 rises in the chamber 17. The cup valve 9 constitutes in part the mixing chamber. The mixture passes through more or less of the ports 16, depending on the height the valve 9 rises or is raised.

Air is admitted to the mixing chamber 18 through casing 1, which has elongated slots 19 and through ports 20 in the sleeve valve 21. The sleeve valve 21 is provided with a throttle connection 22 by which the valve 21 can be rotated to let in more or less air into the same. The connection 22 is adapted to move in the elongated ports 19 and the valve can be rotated far enough to cut off the air supply entirely. A spring 23 has one end inserted in the valve 21 and one end inserted in the casing 1 for automatically bringing the sleeve valve 21 back to normal or closed position. With such structure the explosive mixture can be made more or less rich as may be required. The mixture escapes from the cup valve 9 into the chamber 17 which will

maintain a head of explosive mixture to be fed through the pipe 24 into the manifold 25.

Provision is made for release in case of back-fire. A nipple 26 is cast on the casing 1 and cored out to form a barrel for a plunger 27. The barrel has communication with the chamber 17 by means of an opening 28. The nipple or barrel 26 has a plurality of perforations 29. A cap 30 is screwed on the nipple 26 and a spring 31 bears against the cap 30 and against the plunger 27. In case of back-fire the plunger 27 will yield more or less according to the force of the explosion and so open more or less of the perforations 29.

15 The carburetor will operate in any position, vertical, horizontal, or even in inverted position and may be connected directly to the manifold or by the connection shown in Fig. 1.

20 What I claim is—

1. A carburetor having a casing provided with air and fuel intake ports, a sleeve valve rotatably mounted therein and provided with air intake ports and a cup valve longitudinally movable in said sleeve valve and forming a mixing chamber and provided with discharge ports at different distances from the head of the valve, means for holding said cup valve yieldingly downward, a needle valve operatively connected with said cup valve, and a seat for said needle valve provided with a fuel passage therethrough adjustably mounted in said casing and provided with lateral fuel intake ports.

35 2. A carburetor having a casing provided with air and fuel intake ports and discharge ports, a sleeve valve rotatably mounted in said casing provided with air intake ports adapted to register with the intake ports 40 of said casing, means for rotating said valve to control the amount of air admitted thereto, a cup valve movable longitudinally in said sleeve valve by pressure of explosive mixture and forming a mixing chamber and provided 45 with graduated discharge ports, means for holding said cup valve yieldingly downward, a needle feed valve operatively connected with said cup valve and a seat therefor having a longitudinal fuel passage therethrough 50 and provided with fuel intake ports, and means for longitudinal adjustment of said needle valve seat for controlling the feeding of the liquid fuel.

3. A carburetor having a casing provided 55 with air and fuel intake ports and discharge ports, a sleeve valve rotatably mounted in said casing provided with air intake ports adapted to register with the air intake ports of said casing, means for rotating said valve 60 to control the amount of air admitted thereto and means for automatically returning said sleeve valve to normal position, a cup valve movable longitudinally in said sleeve valve by pressure of explosive mixture and forming 65 a mixing chamber and provided with gradu-

ated discharge ports, means for holding said cup valve yieldingly downward, a needle feed valve operatively connected with said cup valve and a seat therefor provided with a longitudinal fuel passage therethrough and lateral fuel intake ports, and means for longitudinal adjustment of said needle valve seat for controlling the amount of fuel feed.

4. A carburetor having a casing provided with air and fuel intake ports, a sleeve valve rotatably mounted therein and provided with air intake ports adapted to register with the air intake ports of said casing and a cup valve movable longitudinally in said sleeve and forming a mixing chamber and provided with graduated discharge ports, means holding said cup valve yieldingly downward, and a seat for said needle valve provided with a fuel passage therethrough adjustably mounted in said casing and provided with lateral fuel intake ports for receiving fuel from the intake port of said casing.

In testimony whereof, I set my hand this 27th day of December, 1929.

SHEPARD W. WHITEHURST.
